UNITED STATES PATENT OFFICE.

SIDNEY HARTNOLL BEARD, OF PAIGNTON, ENGLAND.

TENNIS-RACKET.

No. 840,467.

Specification of Letters Patent.

Patented Jan. 8, 1907.

Application filed June 5, 1906. Serial No. 820,309.

To all whom it may concern:

Be it known that I, SIDNEY HARTNOLL BEARD, a subject of the King of Great Britain and Ireland, residing at Barcombe Hall, Paignton, in the county of Devon, England, have invented new and useful Improvements in Tennis-Rackets, of which the following is a specification.

My invention relates to improvements in tennis-rackets.

Tennis-rackets depend for their efficiency upon the rigidity with which they are strung and upon the unyielding resistance of the string-surface to the impact of the tennis-ball. Tennis-rackets which are strung with gut string (the material now generally used in their manufacture) soon lose their rigidity, become yielding, and inefficient in consequence of the tendency of the gut strings to stretch slightly. Gut strings also often break as a result of the strain put upon them when the tennis-balls are struck with the racket. It has been proposed to string tennis-rackets with thin metal wire, but, however, with only unsatisfactory results.

Now the object of my improvements is to provide a simple and efficient construction of tennis-rackets strung with the usual gut strings, whereby such rackets are caused to remain rigid and also be durable, neither frequently breaking nor requiring restringing, as is the case with rackets as heretofore constructed.

My improvements consist in the introduction of a number of rigid inextensible metal rods extending across those parts of the racket where the strain comes when the ball is struck. These metal rods, which are preferably made of steel, are situated in the central plane of the racket and may extend across the racket from side to side or from end to end, or diagonally, according to the strength and rigidity required. The metal rods are passed one over the other or through the usual gut strings and are fastened on either side of the frame of the racket by means of heads and washers and of terminal screw-nuts, clenched ends, or other means. Thus a rigid, durable, and almost unbreakable tennis-racket is made.

The accompanying drawings illustrate my invention.

Figure 1 is a face view of a tennis-racket, partly in section; and Fig. 2 is a side view, also partly in section.

55

1 is the wooden frame of the racket, strung in the usual manner with ordinary gut strings 2.

3 represents are rigid, inextensible metal rods, preferably of steel. They extend in the central plane of the racket from end to end 60 of the same. Each rod is formed with a head 4 at one end and with a screw-threaded extremity 5 at the other and is inserted in place through holes formed in the frame of the racket.

65

6 is an internally-screw-threaded sleeve-nut adapted to be screwed upon the screw-threaded end 5 of each rod.

7 is a faceted collar formed on the sleeve. It serves to enable the sleeve to be screwed 70 up and also as a stop for the same. The hole in the frame is widened to receive the sleeve.

Each rod 3 is suitably bent at a greater or less angle at its headed end to suit the curvature of the frame at its respective place of insertion, where a washer 8 is employed to provide an unyielding bearing.

Having now described my invention, what I claim as new, and desire to secure by Letters Patent, is—

80

1. In a gut-strung tennis-racket, the combination with the gut strings, of rigid inextensible metal rods extending across the racket approximately in the central plane thereof, and means for retaining said rods in 85 place, substantially as described for the purpose specified.

2. In a gut-strung tennis-racket, the combination with the gut strings, of rigid inextensible metal rods extending across the 90 racket approximately in the central plane thereof, said rods being headed at one end and screw-threaded at the other end, with sleeve-nuts engaging the screw-threaded ends 95 of said rods, substantially as shown for the purpose specified.

In testimony whereof I have signed my name to this specification in the presence of two subscribing witnesses.

SIDNEY HARTNOLL BEARD.
